UNITED STATES PATENT OFFICE.

JUDSON C. PEWTHIER, OF WASHINGTON, DISTRICT OF COLUMBIA.

TOY PISTOL.

1,291,113.

Specification of Letters Patent. Patented Jan. 14, 1919.

Application filed November 23, 1918. Serial No. 263,877.

To all whom it may concern:

Be it known that I, JUDSON C. PEWTHIER, a citizen of the United States, residing at Washington, in the District of Columbia, have invented certain new and useful Improvements in Toy Pistols, of which the following is a specification, reference being had to the accompanying drawings.

This invention relates to toy pistols and particularly to that class of toy pistols in which an uncoiled wire spring is used for the purpose of projecting the missile.

The general object of this invention is to simplify the construction of toy pistols of this kind and permit them to be very cheaply made and sold.

A further object is to provide improved means for holding the spring under tension and releasing the spring and mounting the spring within the frame of the piston or gun.

Other objects have to do with the details of construction and arrangement of parts as will hereafter appear.

My invention is illustrated in the accompanying drawing, wherein:—

Fig. 1 is a side elevation partly broken away of my improved pistol;

Fig. 2 is a sectional view on the line 2—2 of Fig. 1;

Fig. 3 is a section on the line 3—3 of Fig. 1;

Fig. 4 is a plan view of the blank;

Fig. 5 is a side elevation of a modified form of pistol partly broken away; and

Fig. 6 is a section on the line 6—6 of Fig. 5.

Referring to Fig. 1, it will be seen that the body or frame of the pistol comprises the stock 10 or grip, the body 11 and the barrel 12. Preferably the body 11 and the barrel 12 are made from a sheet metal blank of the form illustrated in Fig. 4, this blank being bent longitudinally upon itself and formed to provide the barrel and the body. The stock or handle 10 is inserted between the two side walls of the blank and riveted or otherwise connected thereto.

The body 11 is formed adjacent the upper edge of the body with a longitudinally extending slot 13, the rear end of which has an upwardly extended portion 14 or notch. Connected to the stock, in a manner which will be later stated, is a wire spring 15. This spring extends downward from the stock and then upward to form a trigger

and then upward and forward to the forward end of the slot 13 and then is laterally extended as at 16 out through said slot and then upwardly extended as at 17. The rear end of the spring 15 is preferably formed with an elongated loop 18 and any suitable fastening device may pass through this loop.

I have shown the fastening device as a staple or double pointed tack 19 driven into the wood of which the stock is made and disposed between the side walls of the body 11. The upper forward corner of the stock 10 is cut away as at 20. The projectile which I design to use in this pistol forms the subject matter of the patent granted to me on the 9th day of April, 1917, No. 1,261,957, this projectile comprising a shaft 21 having a hollow bulbous head 22 formed of wire gauze.

With the construction illustrated, the pistol is rendered operative by drawing back on the portion 17 of the spring 15 until this part 17 is engaged in the notch 14. Then if the downwardly extending looped portion of the spring 15 be drawn rearward either by inserting the finger within the loop or around the forward portion of the loop, the part 17 will become disengaged from the notch 14 and the spring will cause the part 16 to spring forward thus projecting the missile. Now if the rear end of the spring 15 were not connected to the stock or to the body 11 by an elongated loop such as 18, the release of the spring and the forward movement of the portion 17 would sting the finger, but by providing the loop 18 I have found that the rear end of the spring will give when the spring is released from the notch 14 and thus the operator's finger will not be stung by the release of the spring. The stock 10 it will be noted will be disposed at an obtuse angle to the barrel and body 11 so that a finger of the operator will not be caught between that portion of the spring which forms the trigger and the forward edge of the stock.

In Fig. 5, I show another form of the device which is entirely made of sheet metal, by simply stamping and folding a sheet metal blank so as to form the stock 10^a, body 11^a and barrel 12^a all in one piece and in this case the loop 18 of the spring extends loosely around a transversely extending rivet 19^a which is the equivalent of the member 19.

It is to be noted that the pistol may be

cocked by drawing back upon the portion 17 and that this may be accomplished by the thumb of the operator without releasing the grasp on the grip or stock, and further 5 that the notch 14 is sufficiently deep to positively hold the spring in its tensioned position. This device does not require that the shaft of the arrow shall be inserted within the barrel so as to force the free end of the 10 spring rearward and thus tension it. This permits other missiles than arrows to be projected from this gun and causes the device to simulate an ordinary pistol much more nearly than it would if the pistol were 15 loaded by forcing the projectile down into the pistol. Furthermore, it permits the use of an annular projectile fitting around the barrel and made of wire gauze.

The object of making the projectile of 20 wire gauze or with its head of wire gauze is to provide a projectile which will not mar furniture, which will not break windows or mirrors and which will not hurt any one whom it may strike. Furthermore this particular type of projectile is to be used for the 25 purpose of killing insects such as water bugs, flies or the like. The pistol and projectile are sufficiently accurate at short distances for this purpose and considerable amusement may be afforded to the user.

The object in cutting away the upper end 30 of the stock as at 20 is to permit the rear portion or leg of the spring to take a position of greater inclination to the axis of the barrel when the spring is cocked than is taken when the spring is released. The elongated loop at the rear extremity of the spring permits the spring to shift when cocking the spring and when it is released 35 40 so that as before stated no stinging jar will be transmitted to the finger of the operator.

While I have illustrated certain details of construction and have illustrated my invention as applied to a toy in the form of a pistol 45 I wish it understood that various changes might be made in these details without departing from the spirit of the invention and it is also obvious that the device might be applied to a toy in the form of a gun.

50 I claim:—

1. A toy pistol having a frame including a stock and body, the body being formed with a longitudinally extending slot having an angularly extending notch at its rear end, 55 a downwardly looped spring operatively attached to the frame of the pistol adjacent the stock and extending downwardly from said point of attachment and then upward and laterally through said slot to provide 60 means whereby the free end of the spring

may be drawn backward into engagement with the notch, the rear end of the spring being swingingly connected to the frame.

2. A toy pistol having a frame including 65 a stock, a body and a barrel, the body being formed with a longitudinally extending slot, the rear end of the slot having an upwardly extending notch, and a spring formed to provide a trigger loop extending below the body, the rear upwardly extending end of 70 the spring having an upwardly extending elongated loop, a member operatively connected to the frame and passing through said loop, the forward end of the spring being upwardly and forwardly extended 75 into the body and then laterally bent to extend out through said slot and then upwardly bent.

3. A toy pistol having a frame including 80 a body and a barrel formed of one piece of sheet metal bent longitudinally upon itself, one of the side walls of the body having a longitudinally extending slot formed at its rear end with an upwardly extending notch, a spring bent to form a trigger loop, 85 the rear end of the spring being formed with an elongated upwardly extending loop, a member on the frame around which said last named loop passes and by which the spring is pivotally and shiftably connected 90 to the frame, the forward end of the spring extending upward between the side walls of the body and then laterally bent and extending out through the slot and then upwardly extended.

4. A toy pistol including a frame formed 95 of a wooden stock or grip and a body or barrel formed of one piece of sheet metal folded longitudinally upon itself, one of the side walls of the body having a longitudinally 100 extending slot having at its rear end an upwardly extending notch, the upper forward corner of the stock being cut away, a staple disposed between the walls of the body adjacent the cut-away portion of the stock and 105 inserted into said stock, and a spring, one end of which is formed to provide an elongated loop embracing said staple, the spring then extending downward and then upward to form a trigger loop and then upward 110 between the walls of the body, then laterally out through said notch and then upward.

In testimony whereof I hereunto affix my signature in the presence of two witnesses.

JUDSON C. PEWTHER.
